United States Patent Office.

J. P. THEODORE LANG, OF WASHINGTON, DISTRICT OF COLUMBIA.

Letters Patent No. 64,775, dated May 14, 1867.

IMPROVEMENT IN STEAM-ENGINE GOVERNORS.

The Schedule referred to in these Letters Patent and making part of the same.

TO ALL WHOM IT MAY CONCERN:

Be it known that I, J. P. THEODORE LANG, of the city and county of Washington, and District of Columbia, have invented a new and improved Automatic Cut-Off for Steam, &c.; and I do hereby declare that the following is a full, clear, and exact description thereof, reference being had to the accompanying drawing, making a part of this specification, in which like parts are indicated by like letters in the several figures.

The nature of my invention consists in the construction of a governor and valve, and combining them so as to afford immediate self-adjustment whereby to produce upon the steam piston a variable effective pressure, thereby regulating the power and speed.

To enable others skilled in the art to make and use my invention, I will proceed to describe its construction and operation. In the drawings—

Figure 1 is an elevation of my machine.

Figure 2 shows the balls or weights in the act of adjustment.

Figure 3, plan and elevation of valve and covering.

It is well known to all skilled in the operations of machinery, particularly steam, water, and other power, that it is desirable to have a governor sensitive to the small and momentary variations of speed of the main driving-shaft. To effect this, I propose a contrivance which forces the weights of the governor up or down an inclined guide. This insures the desired movement of the governor, which exclusively controls a valve to be hereafter described.

In the drawings, A represents a foundation for the governor. a and b represent bevel gears. B is a support for the governor. C is its upright shaft. D is a loose collar, to which elbow-levers d d are pivoted at e e. To the ends of these levers are attached the weights E E, either rigidly or by means of springs f f. F is a collar fastened to the shaft C, having on its upper surface friction-rollers, g, on which the loose collar D rests and plays. Above D is another collar, G, secured to shaft C. Between these collars F and G the loose collar D rotates without rising or falling. H H are inclined, curved, slotted guides, which are fastened to a collar, h, secured to shaft C, or they may be fastened directly to shaft C. The guides shown are curved and slotted, and in these slots the arms d work or play, these arms having on their lower ends friction-rollers d¹, held in place by a recess in the arm above, and a collar, d², below, thus counteracting friction on the guides or lessening it. Springs f are fastened to the ends of the arms d, supporting the weights E. The arms d have elbows, d³, and connected with these are rods i to transmit motion to a sliding collar, k, above, embracing shaft C. This collar is provided with a groove, in which the forked lever l gears. This lever is supported by a standard, J, being pivoted at j. The other end of said lever l is also forked, and embraces a ring, l, to which it is pivoted, forming a kind of universal joint. This ring is confined between the thumb-nuts m m, screwed on to a valve-rod, K, which operates the valve-cover L. The valve-seat M forms an essential part of the steam-chest which encloses the main valve. The circumference of valve-seat M is provided with ports q for the entrance of steam, and its top is closed and exposed to the pressure of steam. This valve-cover is not continuous, having on its sides flanges n n, which may be regulated by set-screws o and check-nuts p. The raising or lowering of the valve-cover L regulates the quantity of steam entering the ports q of the valve-seat M.

The operation is as follows: In fig. 1 the-governor is shown at rest, or the weights down. Letting steam on the engine will operate; and the balls will immediately rise upwards and outwards, thereby regulating the supply of steam at once by partially closing the ports q. Fig. 2 shows the ball E in three different positions whilst operating. Supposing the ball or balls to be in a desired position or positions, at a desired speed, represented by E in said figure, the speed being accelerated, the ball will move up to the position as shown by E²; or, if the speed be retarded, the ball or balls will fall or move down, as shown by E¹, in both cases operated instantly. This is effected by the guides, which, moving faster or slower than the desired speed, will, with the aid of the inertia of the balls, force them either up or down, in either case operating the valve instantly, in the first case partially closing the ports q, and in the second exposing more area of the same. The springs f are intended to overcome sudden jars or jerks. The rods i, transmitting the governing power, need not be above the loose collar D, and need not be fastened to the end of the elbow d³, but may be arranged the same as on common governors, this without altering the nature of my invention. The location of the upper sliding collar

k may be varied to suit the convenience of the special machinery to which it is to be adapted; for instance, it may be below the collar D. The collar F, with the friction-rollers *g*, may have any other equivalent anti-friction devices; also as to the curved slotted guides, which may be solid and inclined. If solid, friction-rollers above and below will keep the arms *d* in desirable positions. I have essayed these parts in various forms, and of various detailed devices, but have adopted these, believing them to be the best.

Having thus described my invention, I claim—

1. The combination and arrangement of the curved slotted guides H H, collar *h*, arms *d*, friction-rollers *d*¹, springs *ff*, weights E E, collar F, friction-rollers *g g*, loose collar D, rods *i*, collar *k*, constructed, arranged, and operating in the manner substantially as shown and described, and for the purpose set forth.
2. The combination of the valve M and cover L with the governor, substantially as herein set forth.

J. P. THEODORE LANG.
